GUN SEALING MEANS

Donovan R. Berlin and Clem G. Trimbach, Eg-
gertsville, N. Y., assignors to Curtiss-Wright
Corporation, a corporation of Delaware

Application August 28, 1940, Serial No. 354,502

1 Claim. (Cl. 89—31)

This invention relates to accessories for guns, and in particular to protective devices applicable to aircraft machine guns.

Objects of the invention are, to provide a frangible or pierceable gun muzzle cover to protect the gun bore and to prevent the entrance of moisture, sleet, or other foreign matter into the bore; to provide a frangible muzzle cover which may be easily replaced after it has been pierced; and to provide a protecting covering for machine gun barrels of the air-cooled type.

Further objects will become apparent from the description below when read in connection with the drawing, in which:

Fig. 1 is a side elevation of an aircraft wing, including a fixed machine gun and the devices of this invention;

Fig. 2 is a side view of an air-cooled gun barrel showing the devices of the invention in section; and

Fig. 3 is a perspective view of the wing, gun and the devices of the invention.

A machine gun 10 is shown in dotted lines in Fig. 1, the gun being fixedly mounted by conventional means in an aircraft wing 11; the barrel of the gun extends forwardly through the wing leading edge as at 12. As shown in Fig. 2, the gun is normally provided with an embracing perforate sleeve 13, the sleeve protecting the barrel and allowing free cooling airflow thereover.

Probably during the major part of the time when a military aircraft is armed, there will be little or no occasion to use the machine guns, and it is desirable to afford the guns protection against the harmful effects of moisture, dust, and other foreign matter. To this end, we provide a tube 14 which may readily be slipped over the sleeve 13, this tube having a stop 15 at its forward end, engaging the front of the sleeve, and having clamp screws 16 at its rear end to secure it to the sleeve against axial displacement. This tube may be removed at such times as active use of the gun is anticipated. It may be left in place to assist in keeping the gun warm if operation in extremely cold weather is anticipated.

Further protection against foreign matter entering the gun barrel is attained by the use of a muzzle cap 17, comprising a front surface 18 and an integral cylindrical skirt 19 which en-

gages the tube 14, or alternatively, the cooling shield 13 or the front of the gun barrel itself. This cap 17 may be made of thin rubber, or cellulose plastic, or other plastic material, which is either readily pierced by a bullet or readily broken away by the passage of a bullet therethrough but which at the same time is resistant to the effects of moisture and abrasion. After having been pierced, the cap may be replaced after the gun has been serviced upon return of the aircraft to its base.

The use of these simple protective devices will help to assure readiness of the gun for action at all times during flight, and they are particularly effective in preventing damage to the gun should sleet or moisture be present in the atmosphere.

While we have described our invention in detail in its present preferred embodiment, it will be obvious to those skilled in the art, after understanding our invention, that various changes and modifications may be made therein without departing from the spirit or scope thereof. We aim in the appended claim to cover all such modifications and changes.

We claim as our invention:

The combination with an aircraft gun of the kind having a barrel, the muzzle end of which is exposed, and a perforate cooling sleeve carried by said barrel, of an imperforate, non-elastic tube which is open at both ends and which fits over said cooling sleeve, an adjustable element carried by said tube and movable into a perforation in said cooling sleeve to releasably secure said tube onto said sleeve, whereby it may be readily removed preparatory to the use of said gun under normal operating conditions, and a cap-piece which fits over the end of said tube and which is adapted to be blown off when said gun is fired, said tube and cap-piece wholly enclosing the exposed portions of said gun barrel and sleeve to protect them against the elements during periods of non-use and said tube being operative, when it is permitted to remain on said sleeve, to render the enclosed portion of the latter ineffective when the gun is to be fired at such low temperatures as to render the cooling action of said sleeve undesirable.
